UNITED STATES PATENT OFFICE.

CHARLES RICH, HENRY CROW, AND MARCUS RICH, OF NEW YORK, N. Y.

DESIGN FOR HOODS.

Specification forming part of Design No. 5,303, dated October 3, 1871.

To all whom it may concern:

Be it known that we, CHARLES RICH, HENRY CROW, and MARCUS RICH, of the city, county, and State of New York, have invented a new and original Design for a Hood; and do hereby declare that the following is a full, clear, and exact description thereof, which will enable others skilled in the art to make and use the same, reference being had to the accompanying drawing forming part of this specification.

The nature of our design is fully represented in the accompanying drawing, to which reference is made.

A represents the cap or hood proper, and B

the cape, which may be made of any suitable material. C represents an ornamental border of embossed figures on the margin of the cap and cape, and D an embossed figure upon the back of the cap.

What we claim as our invention is—

The design for hoods above described, and illustrated in drawing.
